UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

SELECTIVE SIGNALING SYSTEM.

1,352,217.

Specification of Letters Patent. Patented Sept. 7, 1920.

Application filed August 23, 1916. Serial No. 116,481.

To all whom it may concern:

Be it known that I, WINFRED T. POWELL, a citizen of the United States of America, and a resident of Chicago, county of Cook, 5 and State of Illinois, have invented certain new and useful Improvements in Selective Signaling Systems, of which the following is a specification.

My invention relates in general to selective signaling systems, but is concerned more particularly with selective signaling in automatic telephone systems, in which connections are established through the medium of directly controlled selector and connector switches.

The principal object is to provide in a system of the above general character means for selecting the proper ringing current at the last selector switch just preceding the 20 final selector or connector, thereby rendering possible the use of a single group of connectors for selectively calling the subscribers on a party line.

Inventions along this line have been disclosed before, notably in the recently issued patent to Deakin, #1,185,635, but to the best of my present knowledge all previous attempts have involved the multiplying of the selector levels. For example, in the 30 above mentioned patent to Deakin, each connector group is accessible to calling lines by way of as many selector levels as there are stations on a line.

In my improved system I provide a single 35 group of connector switches for selectively calling each group of party lines and assign to each connector group a single selector level, thereby obtaining a great economy in apparatus. This arrangement is made possible through the use of a new method of 40 ringing current selection in which the proper ringing current is picked out by a preliminary operation of the selector switch.

The particular means and circuit arrangement by which the foregoing and other useful ends are accomplished will be fully described hereinafter, reference being had to the accompanying drawings, which show diagrammatically a complete circuit connection between a calling substation A (Figure 1) and a called substation A' (Fig. 2). The exchange equipment used in setting up the complete connection shown comprises the individual line switch C, the selector E, and 55 the connector F.

Referring now to Fig. 1, the substation A may be of any suitable type or construction, such, for example, as the type disclosed in British patent to T. G. Martin, No. 1419 of 1910. As shown herein it comprises essentially the receiver 2, transmitter 3, switch hook 4, ringer 5 and condenser 6. Being an automatic substation there is also provided a pair of impulse springs 7 and 8 controlled by the impulse wheel 9 through 65 the medium of a finger hole dial (not shown).

The line conductors 12 and 13 of the substation A are connected at the exchange to the individual line switch C which may 70 be of the general type of line switch disclosed in British patent to R. W. James, No. 26,301 of 1906; being, however, of the particular type shown in United States Letters Patent No. 1,078,690, granted Jan. 75 17, 1912, to Frank Newforth. Since line switches of the above type are well known and form no part of my invention an extended description will not be given. It will suffice to say here that through the 80 medium of line switch C the line of substation A, when calling, is given access to a plurality of selector switches, one of which is shown at the right of Fig. 1 and is indicated by reference character E. 85

The master switch D is of the general type of master switch disclosed in the above mentioned British patent to James, No. 26,301 of 1906; being, however, more nearly of the particular type disclosed in the British patent to Martin, No. 1419 of 1910. As is well understood, the function of the master switch is to maintain the plungers of all the idle line switches which it controls in position before the terminals of an idle 95 trunk line.

The selector switch E is of the general type of selector switch disclosed in U. S. Letters Patent No. 815,321, granted March 13, 1906, to Keith, Erickson and Erickson; 100 the side switch and private magnet, however, being omitted, and the circuits being modified to enable the switch to operate in a system in which the impulses are delivered over the two sides of the line in series. 105 Further modifications, supplied in accordance with my invention, have to do with the ringing current selection and will be described later on. A selector switch of the foregoing general type, as is well known, 110

may be operated in response to the first digit of a called number to select one of a number of main groups into which the lines of the exchange are divided. For this purpose the selector E, in common with other similar selectors, may be given access to a number of groups of trunk lines, the trunk lines of each group being terminated in a group of connector switches.

- 10 One of the trunk lines to which the selector E has access is indicated in the drawings by the reference characters 120, 121, 122, and 123 and extends to the connector switch F (Fig. 2), which is of the general type of connector switch disclosed in U. S. Letters Patent No. 815,176, granted March 13, 1906, to Keith, Erickson and Erickson; being, however, of the particular type disclosed in U. S. Letters Patent No. 13,901, reissued 15 April 13, 1915, to Frank Newforth. A connector switch of the foregoing type may be given access to a group of one hundred subscribers' lines and is operable in response to the two last digits in a called number to 20 establish connection with any line in the group.

One of the lines to which the connector F has access is the party line shown in the upper half of Fig. 2 and having the line 30 conductors 12' and 13'. The four substations A', A², A³, and A⁴ are connected in bridge of the line conductors in the usual manner and are similar to the substation A, which has been described, with the exception, however, that the ringers are adapted 35 to respond to different frequencies of ringing current. At the exchange the line conductors 12' and 13' terminate in the individual line switch C' which is similar to 40 the line switch C (Fig. 1).

The special equipment associated with the selector E and which is concerned with the selection of ringing current frequencies comprises the relays 40, 41, and 42, which 45 are controlled through the medium of the usual private wiper 71 and the special wiper 70. These wipers exercise their controlling functions through their engagement with the first sets of contacts in the 7th, 8th, 9th, 50 and 10th levels, which contact sets are set aside in each switch for this purpose. All the remaining contact sets are of course, multiplied in the usual manner and form terminals of trunk lines extending to connector switches, similar to the trunk line shown, but the contact sets mentioned are not multiplied but are wired to the relays of the associated switch. Other special provisions in the selector E comprise an 55 additional winding 55 on the relay 53, whose purpose will be explained, and a set of shaft controlled springs 62, which are provided in addition to the usual off normal contacts 60 and 61. The springs 62 are 60 closed only on the tenth vertical step. 65

The generators R', R², R³, and R⁴ deliver ringing currents of different frequency and are adapted to actuate, respectively, the ringers 105, 205, 305, and 405, at substations A' to A⁴, inclusive. The generator R², 70 delivering preferably current of a frequency of 33 cycles per second is normally in service, but any one of the other generators may be selected, depending on the substation wanted, as will be fully explained in 75 the detailed descriptions of the operation.

For supplying current for operating and talking purposes I have shown a battery B, having its positive pole grounded. Associated with the connector F I have shown an 80 interrupter I and a busy signaling machine Q which are of the usual type and perform the same functions as the same named pieces of apparatus in other automatic systems.

Having given a general description of the 85 apparatus involved I will now proceed to an explanation of the operation of the system. For this purpose it will be assumed that the subscriber at substation A desires to obtain connection with the subscriber at 90 substation A', this being the complete circuit connection shown in the drawing. Inasmuch as a great deal of the apparatus shown is well known in the art, having been fully described in the publications previously referred to, the operation will be described in a more or less general manner, the details being given only in so far as they are concerned with my invention.

Referring to Fig. 1, when the subscriber 100 at substation A removes his receiver to initiate the call, an energizing circuit is completed over the line conductors 12 and 13, for the line relay 16 of the line switch C. Upon attracting its armature, the line relay 16 closes a circuit for the pull-in winding 17. Upon energizing, the pull-in winding operates both the plunger arm 21, and the cut-off armature 22; the former through the medium of its plunger (not shown) 110 forcing the bank springs 30-33, inclusive, into engagement, respectively, with contacts 34-37, inclusive; and the latter disconnecting the line conductors 12 and 13, respectively, from ground and from the line relay 115 16. By the engagement of bank springs 30 and 33, respectively, with contacts 34 and 37, the line conductors 12 and 13 are extended to the double wound line relay 50 of the selector E.

The line relay 50 is accordingly energized over the loop circuit including substation A and, upon attracting its armature, closes a circuit for the slow acting release relay 51. Upon energizing in turn, the relay 51 completes a holding circuit for the line switch C which may be traced as follows: ground at G', contact springs 63 and 64, contact 35, bank spring 31, and holding winding 120 18 to battery B. Since the line relay 16 is 125 186

slow acting, it retains its armature to maintain the pull-in winding 17 energized until after the above holding circuit has been established. A branch of the holding circuit 5 extends by way of conductor 19 to multiple test contacts in the banks of connector switches having access to the line of substation A where by a ground potential on these test contacts the said line is made 10 busy. By the engagement of bank spring 32 with contact 36 the master switch D is operated in well known manner to advance the plungers of all the remaining idle line switches into position before the terminal 15 of the next idle trunk line.

The foregoing operations whereby the line conductors 12 and 13 have been extended to the line relay 50 of the selector E have taken place in response to the removal of the 20 receiver at substation A. The calling subscriber may now manipulate his dial in accordance with the first digit of the desired number, which digit is to determine the frequency of ringing current to be applied 25 to the called line by means of a preliminary operation of the selector E, all as previously mentioned. Since it is required that the generator R' be selected, this generator being the one corresponding to substation 30 A', the first digit of the called number will be the digit 0. When the calling device dial is operated in accordance with this digit the impulse springs 7 and 8 are separated momentarily ten times thereby interrupting 35 a like number of times the energizing circuit of the line relay 50.

At each interruption of its circuit the line relay 50 is deenergized momentarily and sends an impulse from ground through the 40 winding 54 of the slow acting relay 53 and the winding of the vertical magnet 58 in series. The vertical magnet, in response to these impulses, operates to step up the switch shaft until the wipers 70, 71, 72, and 45 73 arrive at the tenth horizontal level of bank contacts. The relay 53 is energized in series with the vertical magnet and being slow acting retains its armature during the 50 series of impulses. Upon the first upward movement of the shaft the off normal contact 60 is closed thereby completing a circuit for the relay 57 which extends from ground G' by way of contact springs 63, 64, and 65, the contact springs 66 and 67 of the now energized 55 relay 53 and the off normal contact 60 to the winding of the said relay 57. Upon energizing, the relay 57 locks itself independent of the relay 53 by means of its upper set of contact springs, and by means of its 60 lower set of contact springs prepares a circuit for the rotary magnet 59 which is held open during the vertical operation of the switch by the relay 53. At this point it should be mentioned that by the closure of 65 the off normal contact 60 the line switching

relay 56, whose right hand terminal is joined to the holding circuit of line switch C and is therefore grounded, is connected in series with the relay 57, the circuit passing through the interrupter contact 88 of the 70 rotary magnet. The junction point 89, however, has already been connected to ground G' as previously described so that the relay 56 is short circuited and remains inoperative for the present. 75

When the slow acting relay 53 deenergizes at the end of the series of impulses it completes by means of its contact springs 66 and 68 the previously mentioned circuit of the rotary magnet, extending from ground G'. 80 Upon energizing, the rotary magnet operates to rotate the wipers 70, 71, 72, and 73 into engagement with the first set of bank contacts of the tenth horizontal level. Near the end of its stroke the rotary magnet also 85 breaks, at its interrupter contact 87, the locking circuit of relay 57; and at its interrupter contact 88, the circuit of the line switching relay 56. Upon deenergizing, the relay 57 breaks the energizing circuit of the 90 rotary magnet which accordingly retracts its armature to again close the interrupter contacts 87 and 88. The operation now depends on the grounded or non-grounded condition of the test contact with which the 95 private wiper 71 is in engagement. Since the wipers were raised to the tenth horizontal level before rotation the private wiper 71 is now in engagement with bank contact 100 81. Current for the energization of relays 40 and 37 in series now flows over the following path: ground at G', right hand winding of relay 40, bank contact 81, private wiper 71, contact spring 91 of relay 56 and its resting contact, interrupter contact 88, 105 off normal contact 60, and the winding of relay 57 to battery B. A branch of the above circuit may be traced from ground G' by way of the right hand winding of relay 41 and the off normal springs 62 (closed on 110 tenth vertical step) to the junction point 92, where it joins the previously traced circuit. It follows that relays 40 and 41 (in parallel) are energized in series with relay 57 via the private wiper 71. Upon energizing, relay 115 41 locks itself over the following path: ground at G', contact springs 63 and 64, conductor 95, contact springs 93, and the left hand winding of relay 41 to battery B. A branch of the above circuit extends by way 120 of contact springs 94, and the left hand winding of relay 40 to battery B, thereby providing a locking circuit for relay 40. It should be mentioned here that the right hand windings of relays 40 and 41 are of 125 low resistance so as to prevent the energization of the much higher resistance line switching relay 56, which as previously mentioned is also in series with relay 57.

Upon the reenergization of relay 57 the 130

rotary magnet circuit is not again completed at this time because of the energized condition of relay 53 which was brought about as follows: When the wiper 70 came 5 into engagement with bank contact 85, simultaneously with the engagement of bank contact 81 by wiper 71, a circuit was completed which extended from ground G^5 by way of bank contact 85, wiper 70, contact 10 springs 96 and 97 of relay 42, winding 55 of relay 53, off normal contact 61, and the release magnet 52 to battery B. Upon the closure of the above circuit the relay 53 and the release magnet 52 are energized in series, 15 the former preventing the closure of the rotary magnet circuit, as previously mentioned, and the latter operating to restore the selector switch to normal position in the usual manner. A branch of the circuit completed over wiper 70 may be traced by way 20 of contact springs 96 and 98 and the winding of relay 42 to battery B. Relay 42 is slow to energize (being provided with a copper slug on its core and having a stiff 25 adjustment) in order to allow time for the operations just described to take place. Upon finally attracting its armature, relay 42 short circuits the right hand windings of 30 relays 40 and 41 by means of its upper three contact springs and the ground connection at G^4 ; and also brings its contact spring 99 into engagement with contact spring 98, whereby the latter spring is separated from 35 contact springs 96 and 97. A locking circuit for relay 42 may now be traced over the following path: ground at G^7 , conductor 95, contact springs 99 and 98, and the winding of relay 42 to battery B.

To sum up the operations brought about 40 in response to the calling of the first digit, the relays 40, 41, and 42 have been energized and locked to ground G^7 , and the selector E has been restored to normal.

The calling subscriber may now operate 45 his calling device in accordance with the second digit of the desired number, which for convenience has been assumed to be the digit 1. In response thereto the selector switch is controlled as before to raise its 50 wipers 70, 71, 72, and 73 to the first horizontal level of bank contacts, after which the wipers are rotated into engagement with the first set of bank contacts of the first level. Upon the deenergization of the 55 rotary magnet after the first rotary step, the operation now as before depends upon the grounded or non-grounded condition of the test contact with which the private wiper 71 is in engagement.

60 Assuming that the trunk line terminating in the first set of contacts of the first level is idle, the test contact 75 will not be grounded and consequently there will be no circuit completed for the relay 57 and the line

switching relay 56 will no longer be short 65 circuited. The said switching relay will then immediately energize in series with relay 57, but is of such high resistance that relay 57 is not operated. By the attracting of its armature, the switching relay 56 opens 70 the circuit of the release magnet at contact springs 101 to provide against the deenergization of relays 50 and 51; shifts the private wiper 71 from its normal connection at the winding of relay 56 to the holding circuit 75 at junction point 102; and disconnects the incoming line conductors from the line relay 50 and extends them by way of the line wipers 72 and 73, bank contacts 76 and 77, and conductors 122 and 123 to the double 80 wound line relay 130 of the connector F.

The line relay 130 is accordingly energized over the calling subscriber's loop, and, upon attracting its armature, completes a circuit for the slow acting release relay 131. 85 Upon energizing in turn, the relay 131 prepares a circuit for the vertical and rotary magnets 132 and 133 in the usual manner and also completes a new holding circuit which may be traced as follows: ground 90 G^6 , contact springs 146 of relay 131, conductor 121, bank contact 75, private wiper 71, contact spring 91 and its working contact to junction point 102, where it joins the previously described holding circuit extending back to the line switch C. A branch of the above circuit extending from junction point 90 by way of the winding of 95 switching relay 56, the interrupter contact 88, the off normal contact 60, and the winding of relay 57 to battery B, whereby the said switching relay is maintained energized to prevent the release of the selector switch. It is understood that the above described holding circuit is completed before 100 the slow acting relay 51 of the selector switch has had time to deenergize.

The calling subscriber may now manipulate his calling device in accordance with the third digit of the desired number, thereby causing another series of interruptions of his line circuit. Responsive to these interruptions the line relay 130 deenergizes a corresponding number of times and sends each time an impulse from ground at G^{10} to the 110 slow acting relay 139 and the vertical magnet 132 in series, side switch wiper 142 being in its first position. The vertical magnet, in response to these impulses, steps up the shaft until the wipers 160, 161, and 162 115 stand opposite the horizontal level of bank contacts in which the line of substation A' terminates. Relay 139, being slow acting, retains its armature during the series of impulses and maintains a circuit from 120 ground at G^{11} for the private magnet 138 and the wiper cut-off relay 136 in parallel. At the end of the series of impulses, the 125

relay 139 deenergizes and breaks the circuit of the private magnet, which latter controls the side switch wipers in the usual manner to advance them to their second position.

The subscriber at substation A may now operate his dial in accordance with the fourth and final digit of the desired number, resulting as before in deenergizations of the line relay 130. Now, however, side switch wiper 142 being in its second position, the line relay sends impulses to the slow acting relay 139 in series with the rotary magnet 133. The rotary magnet operates in response to these impulses to rotate the wipers 160, 161, and 162 until they rest, respectively, upon bank contacts 163, 164, and 165, these contacts forming the terminal of the line of substation A' in the bank of connector H. The private magnet 138 and the wiper cut-off relay 136 are energized during the final series of impulses as before, the latter disconnecting the line wipers during rotation and the former, upon deenergizing, controlling the side switch wipers to advance them to their third position, it being assumed that the line of substation A' was idle when called.

As side switch wiper 143 comes into engagement with its third position contact point, a circuit is completed for the cut-off winding 18' of the line switch C' as follows: ground at G¹², side switch wiper 143 (in third position), wiper 161, bank contact 164, and winding 18' to battery B. By the closure of the above circuit the cut-off armature 29' is operated to disconnect the line conductors 12' and 13', respectively, from ground and from the line relay 16'. Ground at G¹² also extends to multiples of bank contact 164 in the banks of other connectors of the group, thereby making the line of substation A' busy to other calls.

By the engagement of the side switch wipers 144 and 145 with their third position contact points the connection between the calling and called substations is completed, relay 136 being deenergized. By the engagement of side switch wiper 142 with its third position contact point, a circuit is completed for the ringing relay 137 in series with the interrupter I, whereby ringing current from generator R' is projected intermittently out over the line of substation A' to operate the signal 105 in bridge thereof. The path for the ringing current may be traced as follows: ground at G¹³, generator R', contact springs 103 of relay 40, contact springs 104 of relay 41, contact springs 112 of line switching relay 56, wiper 70, bank contact 74, trunk conductor 120, contact springs 106 of ringing relay 137, contact springs 107, wiper 160, bank contact 163, the called subscriber's line and substation ringers in

bridge thereof, bank contact 165, wiper 162, 65 contact springs 108, and contact springs 109 to ground at G¹⁴. As previously mentioned, the ringer 105 at substation A' is the ringer adapted to respond to the particular frequency of ringing current delivered by generator R'.

The subscriber at substation A has now established the required connection with the line of substation A' and the bell at the latter substation is being rung to attract the 75 attention of the called subscriber. When the called subscriber removes his receiver from the hook a circuit is completed for the double wound back bridge relay 141 in the well known manner. Upon attracting its 80 armature, relay 141 closes a circuit for the ring cut-off relay 135 which relay locks itself to ground at G¹² and also opens the circuit of the ringing relay 137, thereby stopping the ringing operation. As a further result 85 of the energization of relay 141 the incoming line conductors 122 and 123 are reversed as regards their connection with the windings of line relay 130. The latter operation is without importance in the system shown 90 here, although it is provided in case it is desired to operate meters or similar apparatus.

The calling and called subscribers may now converse without further effort. Current for the transmitter at substation A is supplied through the windings of the line relay 130, while current for the transmitter at substation A' is supplied through the windings of the back bridge relay 141. The voice 95 currents follow the path shown in the heavy lines which, it is thought, will be apparent without further amplifying the explanation.

When the conversation is completed both subscribers will hang up their receivers. By 100 the replacement of the receiver at substation A the circuit of the line relay 130 of the connector F is broken. Upon deenergizing, relay 130 breaks the circuit of relay 131, which relay, upon deenergizing in turn, 110 closes a circuit for the release magnet 140, whereupon the connector F is restored to normal in the usual and well known manner. As a further result of the deenergization of relay 131, ground G⁹ is removed from 115 the holding circuit extending back to the selector E and the line switch C. The selector and line switch therefore are also restored to normal. In addition the relays 40, 41, and 42, whose locking circuits have 120 been supplied with ground over the holding circuit, retract their armatures whereupon all the apparatus will have been restored to normal in readiness for another call.

The operation of a connector switch such 125 as connector H when connection is attempted with a busy line is well known and has been fully described in the publications pre-

viously mentioned. Since my invention involves nothing new in connection with this feature of the operation the description thereof will be omitted.

Having described the operations incident to the establishing of a connection with subscriber A', I will now describe briefly the operation of signaling the substations A², A³, and A⁴. Since all the substations mentioned are on the same party line the operation of connecting with any one of them will be identical with the operations already described with the exception of the ringing current selection. We need consider therefore only the first digit of the call numbers and the operation of the selector E in response thereto.

Assuming that connection is desired with substation A², requiring the selection of generator R², the first digit to be called is the digit 7. Since the bank contacts 78 and 82 of the seventh level are both permanently grounded, the selector E will be operated and released and the relay 42 will be locked up as previously described, but neither of the relays 40 and 41 will be operated. With both these relays deenergized the generator R² is in service, as will be readily apparent upon tracing the circuit. If substation A³ is wanted, the first digit called is the digit 8. It will be observed that the right hand winding of relay 41 is connected to the bank contact 79 of the eighth level. Consequently, when the selector E is operated in response to the calling of the digit 8 and is released as before, the relay 41, in addition to the relay 42, will be energized. With relay 41 energized and relay 40 deenergized, the generator R³, corresponding to substation A³, is in service. Assuming finally that substation A⁴ is wanted, the proper digit to be called for the frequency selection is the digit 9. The right hand winding of relay 40 being connected to the bank contact 80 of the ninth level, the said relay 40 is energized to select the generator R⁴.

It will be observed that whether the first digit called is 7, 8, 9, or 0, the relay 42 is operated and locked up in any case with the result that the right hand windings of relays 40 and 41 are short circuited by ground G⁴. This is done in order to prevent these relays from operating on the second digit of a called number, in case they were left deenergized after the first digit was called. It would not be sufficient merely to open the circuits of these relays, for the bank contacts 78, 79, 80, and 81 must have ground potential on them in order to permit the selector E to pass over the first contacts in the seventh, eighth, ninth and tenth levels when it is operated in response to the second digit of a called number and the selection of an idle trunk is required.

Having described my invention what I

consider to be new and desire to have protected by Letters Patent will be pointed out in the appended claims.

What I claim as my invention is:

1. In a telephone system, means comprising a selector and connector switch for connecting a calling and a called line, together with means individual to said selector for selectively signaling the stations on the called line controlled in a preliminary operation of the selector switch separate from the trunk selecting operation thereof. 75

2. In a telephone system, means comprising a selector and connector switch for connecting a calling and a called line, together with means individual to said selector for selectively signaling the stations on the called line controlled in a preliminary operation of the selector switch, and means for automatically releasing said selector after the preliminary operation thereof and before the connection is completed. 85

3. In a telephone system, a party line, means including a selector switch and a connector switch for extending a connection to said party line, means individual to said selector for selectively signaling the stations on said party line, and means for giving said selector a preliminary movement to determine the character of the signaling operation and for then operating said selector to extend the connection. 95

4. In a telephone system, a party line, means including a selector switch and a connector switch for extending a connection to said party line, means individual to said selector for selectively signaling the stations on said party line, means for giving said selector a preliminary movement to determine the character of the signaling operation, and means for automatically releasing said selector after the preliminary movement thereof and before the connection is completed. 100

5. In a telephone system, a plurality of connector switches, a plurality of ringing current generators, a selector switch, means for causing successive operations of said selector to select one of said generators and one of said connectors, and means for automatically releasing said selector between successive operations thereof. 115

6. In a telephone system, a selector switch and a plurality of connector switches accessible thereto, a plurality of ringing current generators, and means for operating said selector in response to two digits of a called number to select one of said generators and one of said connectors. 120

7. In a telephone system, a selector switch and a plurality of connector switches accessible thereto, a plurality of ringing current generators, means for operating said selector in response to one digit of a called number to select one of said generators, and means 130

for operating said selector in response to a succeeding digit of the called number to select one of said connectors.

8. In a telephone system, a selector switch having vertical and rotary motion, groups of connector switches accessible to said selector, said groups selectable in the vertical movement thereof, ringing current generators also selectable in the vertical movement of said selector, and means for causing successive vertical movements of said selector to select one of said generators and one of said connector groups.

9. In a telephone system, a connector switch, a selector switch for extending connection to said connector, ringing current generators selectable by said selector, and means for causing successive operations of said selector to select one of said generators and to extend the selected generator to said connector.

10. In a telephone system, a plurality of trunk lines each extending to a connector switch, a selector switch having access to said trunk lines, a plurality of ringing current generators, and means for causing successive operations of said selector to select one of said generators and to connect the selected generator to one of said trunk lines.

11. In a telephone system, a connector switch, a selector switch for extending connection to said connector, ringing current generators selectable by said selector, means for causing successive operations of said selector to select one of said generators and to extend the selected generator to said connector, and means for automatically releasing said selector between successive operations thereof.

12. In a telephone system, a plurality of trunk lines each extending to a connector switch, a selector switch having access to said trunk lines, a plurality of ringing current generators, means for causing successive operations of said selector to select one of said generators and to connect the selected generator to one of said trunk lines, and means for automatically releasing said selector between successive operations thereof.

13. In a selective signaling system, the combination with a plurality of ringing current generators, of means controllable by a calling subscriber for selecting one of said generators, a trunk line common to a plurality of said means for extending connection to a called line, said means adapted to select a generator in one operation and to extend a connection to said trunk line in a separate operation, and means for applying a selected generator to the called line via a conductor of said trunk line.

14. In a selective signaling system, four generators arranged in pairs, a relay for selecting either pair, a second relay for se-

lecting either generator of the selected pair, and means whereby the selected generator is applied to a subscriber's line.

15. In a selective signaling system, four generators arranged in pairs, a relay for selecting either pair, a second relay for selecting either generator of the selected pair, means whereby said relays are controlled by a calling subscriber, and means whereby the selected generator is applied to a called line to signal a subscriber thereon.

16. In a telephone system, an automatic switch having wipers for use in connecting a calling and a called line, a plurality of stations on the called line, a plurality of ringing current generators for selectively signaling said stations, and relays controlled in the movement of said wipers by said switch, said relays provided with means whereby they conjointly accomplish the selection of any one of said generators.

17. In a telephone system, means including a plurality of automatic switches each having wipers for connecting a calling and a called line, a plurality of stations on the called line, a plurality of ringing current generators for selectively signaling said stations, and relays associated with one of said switches and controllable by the movement of the wipers of said switch when operated by the calling subscriber, said relays provided with means whereby they conjointly control the selection of any one of said generators.

18. In a telephone system, means for connecting a calling and a called line including a plurality of trunk lines each terminating in a connector switch, a plurality of stations on the called line, a plurality of ringing current generators for selectively signaling said stations, means whereby the calling subscriber selects one of said generators in one operation and one of said trunk lines in a separate operation and means whereby the selected generator is extended over a conductor of the selected trunk line to the associated connector switch.

19. In a telephone system, a plurality of selector switches each having movable terminals, fixed multiple terminals in each selector accessible to the movable terminals thereof, fixed non-multiple terminals in each selector also accessible to the movable terminals thereof, and selective ringing equipment associated with each selector and adapted to be selectively operated by the co-operation of said movable and non-multiple fixed terminals.

20. In a party line telephone system, a plurality of connector switches, a plurality of selector switches, trunk lines connecting the two kinds of switches, ringing current generators for selective signaling associated with said selectors, and means in each selector for selecting one of said generators in

response to one digit and for extending connection therefrom over one of said trunk lines to one of said connectors, and means for operating the selected connector in response to another digit to connect with and signal a called line.

21. In a telephone system, a connector switch, a selector switch for extending connection to said connector, ringing current generators selectable by said selector, means for causing successive operations of said selector to select one of said generators and to extend the selected generator to said connector, a party telephone line accessible to said connector, and means for then operating said connector to connect the selected generator with said party line to signal a called subscriber.

22. In a selective signaling system, the combination with a plurality of ringing current generators, of means controllable by a calling subscriber for selecting one of said generators, a trunk line for extending connection to a called line, having a pair of talking conductors and means for applying a selected generator to the called line, separate from the talking conductors via a conductor of said trunk line, said last means comprising an automatic progressively movable switch at each end of said trunk line.

23. In a selective signaling system, four generators arranged in pairs, a relay for selecting either pair, a second relay for selecting either generator of the selected pair, means whereby said relays are controlled by a calling subscriber, and means whereby the selected generator is applied to a called line to signal a subscriber thereon, said last means comprising an automatic progressively movable switch.

24. In a selective signaling system, four generators arranged in pairs, a relay for selecting either pair, a second relay for selecting either generator of the selected pair, means whereby said relays are controlled by a calling subscriber, and means whereby the selected generator is applied to a called line to signal a subscriber thereon, said last means comprising a plurality of automatic progressively movable switches.

25. In a telephone system, an automatic switch for use in connecting a calling and a called line, a plurality of stations on the called line, a plurality of ringing current generator for selectively signaling said stations, relays controlled by said switch, said relays provided with means whereby they jointly accomplish the selection of any one of said generators, and a second automatic switch for completing a connection from the selected generator to the called line.

26. In a telephone system, a plurality of selector switches each having movable terminals, fixed multiple terminals in each

selector accessible to the movable terminals thereof, fixed non-multiple terminals in each selector also accessible to the movable terminals thereof, selective ringing equipment associated with each selector and adapted to be selectively operated by the co-operation of said movable and non-multiple fixed terminals, and connector switches accessible to said selector switches and selectable through the co-operation of said movable and multiple fixed terminals.

27. In a selective signaling system, a plurality of sources of current of different character, a plurality of lines, a plurality of signals on each line corresponding to said different sources, a plurality of trunk lines each terminating in a progressively movable automatic switch, said switches having access to said lines, another progressively movable automatic switch having access to said trunk lines, means for selecting one of said current sources, means for operating said last switch for selecting one of said trunk lines and its associated automatic switch and for establishing a connection over the selected trunk line from the selected current source to the selected switch, and means for then operating the selected switch to connect the selected current source to one of said lines to operate a desired signal thereon.

28. In a selective signaling system, a plurality of sources of current of different character, a plurality of lines, a plurality of signals on each line corresponding to said different sources, a plurality of trunk lines each terminating in a progressively movable automatic switch, said switch having access to said lines, another progressively movable automatic switch having access to said trunk lines, means including relays individual to said last switch for selecting one of said current sources, means for operating said last switch for selecting one of said trunk lines and its associated automatic switch and for establishing a connection over the selected trunk line from the selected current source to the selected switch, and means for then operating the selected switch to connect the selected current source to one of said lines to operate a desired signal thereon.

29. In a selective signaling system, a pair of line conductors, a plurality of current sources, a plurality of signaling devices corresponding to said sources connected to both conductors, an auxiliary conductor, a switch for connecting said auxiliary conductor with any one of said sources, and means for placing the connected auxiliary conductor into connection with one of said line conductors, whereby any one of said signals may be operated.

30. In a selective signaling system, a pair of line conductors, a plurality of current sources, a plurality of signaling devices cor-

responding to said sources connected to both conductors, an auxiliary conductor, a switch for connecting said auxiliary conductor with any one of said sources, means for placing the connected auxiliary conductor into connection with one of said line conductors, whereby any one of said signals may be op-

erated, and means for automatically controlling the operation of said switch over said line conductors for the purpose set forth. 10

Signed by me at Chicago, Cook county, Illinois, this 12th day of August, 1916.

WINFRED T. POWELL.
